LINE CONNECTOR DEVICE

John L. Yonkers, Evanston, Ill.

Application January 9, 1942, Serial No. 426,164

2 Claims. (Cl. 24—243)

This invention relates to a connector and also to a tool for operating thereon and has particular reference to a tap connector for use on transmission line wire or the like. As is well known, high tension transmission line wire is generally of hard drawn copper or aluminum on a steel core and frequently requires a tap line connection to be made or taken down. In order to establish a satisfactory connection, it is important that no permanent damage or deformation to the line wire results. Furthermore, in making or breaking such tap connection it is frequently necessary to operate while the line is "hot." By virtue of the invention described herein, a simple and effective connector is provided and simple and effective means are provided for applying or removing the connector to and from the transmission line wire with a minimum of effort and danger.

For a further understanding of the invention reference is made to the drawings wherein:

Figure 1 shows a tool in perspective;

Fig. 2 shows the tool operating on a connector, certain parts being in section;

Fig. 3 is an exploded view of a connector;

Fig. 4 is a bottom view of a connector;

Fig. 5 shows a top view on line 5—5 of Fig. 6 of a modified tool operating on a connector;

Fig. 6 is a section on line 6—6 of Fig. 5;

Fig. 7 is a bottom view of the modified tool;

Fig. 8 is a section on 8—8 of Fig. 7; and

Fig. 9 is a section on 9—9 of Fig. 8.

Referring first to Figs. 1 to 4 inclusive, a line 10 is to have a tap 11 connected thereto. The tap is maintained on the line by the connector shown in exploded form in Fig. 3. This connector consists of a split bolt having a rounded head 13 and arms 14 and 15. Arms 14 and 15 are threaded as a unit to form a split bolt having a space 16 between the arms. Cooperating with split bolt 12 is a nut 18 consisting of a nut proper 19 carrying a clamping head 20. Clamping head 20 has a pair of slots 21 and 22 through which bolt arms 14 and 15 may pass. The nut and clamping head are relatively rotatable around the nut axis. The head may be supported on the nut in any suitable manner and as shown is carried by a strap 23, which is secured, as by riveting, to central portion 24 of clamping head 20 and which extends down along the inside of the nut to the remote end 26 thereof. The strap ends are then flared out at 27 to lock the nut and head together against separation. Strap 23 should be narrow enough to lie within space 16 of the split bolt. The clamping head is relatively

massive and has sufficient body and size, as well as shape, to be gripped by a wrench. The clamping head is made of a good conductor like copper, brass or bronze and preferably the nut and retaining strap 23 are also of good conducting material. When installed, the line and tap wires are clamped between clamping head 20 and bolt head 13.

A special tool may be provided so that the clamp 10 may be installed or removed easily. As shown in Figs. 1 and 2, this tool has a primary wrench 30 having a handle portion 31 and jaws 32 and 33. Jaws 32 and 33 may have any suitable shape and are adapted to engage clamping head 20. The clamping head is shown here as square. Any other shape may be used. Preferably wrench jaws 32 and 33 have a thickness of the order of that of clamping head 20 and is preferably somewhat thinner.

Wrench handle 30 carries at the free end thereof a handle 35. The two are hinged together at 36 and a spring 37 may be provided for normally urging wrench 30 against handle 35. Handle 35 has a rounded apertured end 39 within which is rotatably mounted a socket wrench 40. The rotatable mounting may be secured in any desired manner. Thus socket wrench 40 has a circumferential outer groove 41 within which a split ring 42 may be disposed. Split ring 42 may be secured to end 39 by screws 43.

Socket wrench 40 is adapted to engage nut 19. A simple means for turning socket wrench 40 is provided. Thus socket wrench 40 may have a body long enough to extend below nut 19 (as seen in Fig. 2) and is provided with diametrically disposed apertures 45. A fork 46 carries pins 47 at the ends thereof and these pins extend into apertures 45. A knurled handle 50 on fork 46 completes the construction.

To use the tool, primary wrench 30 is moved to engage clamp head 20. Socket wrench 40 is turned so that it may engage nut 19 and permit handle 35 to come up parallel to handle 30. Then socket wrench 40 may be operated by knurled handle 50 to tighten or loosen clamp head 20. It is clear that all the forces used on the entire clamp are taken up by handles 30 and 50. No turning force on line wire 10 is applied. The entire tool is always on the same side of line 10. The operation is so simple and convenient that a lineman can work with gloves. The handles may be made of insulating material if desired.

In this form of the invention, the relative sizes of clamping head 20 and nut 19 are unimportant. Thus clamping head 20 may have a wrench size

equal to, larger or smaller than nut 19. The wrench size referred to is the distance between oppositely gripped surfaces and has no reference to square, hexagonal or other wrenches. However, by having nut 19 so shaped that parts project beyond clamping head 20, as by having clamping head square and nut 19 hexagonal for the same size wrench, jaws 32 and 33 are locked in position as shown in Fig. 2. At the same time, socket wrench 40 is maintained in position by the 10 spring hinge action.

It is clear that this form of tool may be used with ease. The two handles remain close together on the same side of the wire. The tool is locked into position so that no delicacy in manipulation is necessary as would be the case with several wrenches. This is an important consideration when working in dangerous or barely accessible locations.

Referring now to Figs. 5 to 9 inclusive, a modified tool is shown. The clamp remains substantially the same. In this form primary wrench 130 has a rounded end 131 with a nut engaging aperture 132 of any suitable shape. This aperture normally engages clamp head 20. Rotatably mounted on one side of end 131 is a socket wrench 140. Socket wrench 140 may be mounted in any suitable manner. Thus socket wrench 140 may have an outwardly extending peripheral flange 141 engaged by an annular Z 142 secured to end 131. In this form, it is necessary that clamp head 20 be as large or larger than nut 19 so that primary wrench opening 132 may clear nut 19.

Socket wrench 140 preferably has an interior shoulder 143 defining the end of the socket wrench part and thus limiting movement of the socket wrench up (as seen in Fig. 6) toward the top of the clamp. Both the clamp and nut are proportioned so that in the top position of the tool, as seen in Fig. 6, shoulder 143 engages the bottom of the nut. In the event that nut 19 is smaller than clamp head 20, then it is clear that socket wrench 140 will be stopped by the bottom of clamp head 20.

For turning socket wrench 140, a handle 150 having fork tines 151 and 152 is provided. Pins 153 carried by the tines engage in apertures 154 in the bottom part of socket wrench 140.

It is clear that the tools are simple, easy to operate and highly efficient. The tools are complete in themselves and by controlling the han-

10 dle size may be made to exert a predetermined turning force on connectors. This feature is important. With ordinary connectors and wrenches, it has been common for connectors to be twisted and mutilated during installation. This makes it impossible to use the connector again and may result in damage to the line wire. With the connector disclosed here, the turning effort for tightening or loosening is exerted on the nut and clamping head. The split bolt itself has no turning movements and is merely tensioned during tightening of the connector. Thus the split bolt of the invention may be made of thinner material than has been the practice without sacrificing strength since even copper has substantial tensile strength.

What is claimed is:

1. A connector for joining a tap line to a transmission line comprising a bolt having a shank, 20 a slot extending from one end of a shank and terminating at the head to form a bight for receiving wires to be joined, a flat washer on said shank having a web portion in the slot of said shank, said washer having a tool engageable peripheral surface, and a nut on said shank for moving the flat washer toward the bight of the bolt, whereby when a high tension line and a wire are placed between the might of the bolt and the web of the washer a lineman may, from that side of the connector away from the transmission line, hold the bolt from rotation by holding the washer while at the same time drawing up the nut.
2. A connector comprising a bolt having a shank, 30 a slot extending from one end of a shank and terminating at the head to form a bight for receiving wires to be joined, a clamping member on said split shank having a web portion in the slot of the split shank, said clamping member having a tool engageable peripheral surface on that side of the web portion away from the bight of the split shank, and a nut on said shank for moving the clamping member toward the bight of the bolt, whereby when two wires are pressed in the bight of the bolt and the clamping member is moved against them, a lineman may, from a single side of the wires hold the bolt from rotation by holding the peripheral surface of the clamping member while at the same time drawing up on the nut.

JOHN L. YONKERS.
